CONFECTION STICK

Frank A. Biehl, Barberton, Ohio, assignor to The Diamond Match Company, New York, N. Y., a corporation of Delaware

Application August 17, 1950, Serial No. 11,793

Term of patent 14 years

(Cl. D82—2)

To all whom it may concern:

Be it known that I, Frank A. Biehl, a citizen of the United States, residing at Barberton, in the county of Summit and State of Ohio, have invented a new, original, and ornamental Design for a Confection Stick, of which the following is a specification, reference being had to the accompanying drawings, forming part thereof.

Fig. 2 is a side elevational view thereof; and Fig. 3 is a section on the line 3—3 of Fig. 2 looking in the direction of the arrows.

I claim:

The ornamental design for a confection stick, as shown.

FRANK A. BIEHL.
